ATTORNEY.

UNITED STATES PATENT OFFICE.

ARTHUR BURGESS, OF PHILADELPHIA, PENNSYLVANIA, ASSIGNOR TO
JOSEPH H. BROMLEY, OF PHILADELPHIA, PENNSYLVANIA.

DESIGN FOR A LACE CURTAIN.

SPECIFICATION forming part of Design No. 36,021, dated August 19, 1902.

Application filed June 25, 1902. Serial No. 118,175. Term of patent 7 years.

To all whom it may concern:

Be it known that I, ARTHUR BURGESS, a subject of the King of Great Britain, residing at Philadelphia, in the State of Pennsylvania, have invented and produced a certain new, original, and ornamental Design for Lace Curtains, of which the following is a full, clear, and exact description, reference being had to the accompanying drawings, forming a part of this specification.

My invention relates to the surface ornamentation of lace-curtain fabrics in which the ornamental pattern or design is produced in the weaving; and it consists in the ornamental design for a lace curtain as illustrated in the drawing, in which is represented a curtain having a border embodying my new design, the field or body portion of the curtain being shown blank or plain.

The characteristic features of my curtain design consist of a continuous edge border on two sides of a curtain-body, A being the long side, and B the short side, at right angles with each other, said border consisting of two par-

allel and narrow plain-surface outer edges *a* 25 and *b* and another and central plain ground surface *c*, comparatively wide and parallel with the outer plain edges *a* and *b*. Said plain-surface edges *a* and *b* are connected with the intermediate central plain surface *c* 30 in the pattern by two parallel rows of open lacework figures *d*, said lacework effect relatively to said plain-surface portions *a*, *b*, and *c* being a distinguishing feature of the concrete pattern. The intermediate central 35 ground surface *c* is filled in with a row of figures *e*, representing empire wreaths.

I claim as new and of my invention—

The ornamental design for a lace curtain substantially as shown and described. 40

In testimony whereof I have hereunto affixed my signature this 31st day of May, A. D. 1902.

ARTHUR BURGESS.
